UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

PUSHER PLATE FOR SLICING MACHINES

Application filed July 5, 1929. Serial No. 376,071.

My invention relates to an improvement in slicing machines of the type in which a rotary knife is employed in combination with a gauge plate for determining the thickness of the slices and a work support upon which the work is conveyed across the face of the gauge plate and against the cutting edge of the knife. The general object of my invention is the provision of an improved face or 10 pusher plate operative for thrusting the work against the gauge plate after holding it in position during the movement of the work past the cutting edge of the knife. One object of my invention is the provision of a 15 pusher plate which shall be vertically adjustable in relation to the work. Another object is the provision of such a plate which is adapted to engage the top of the work and to thrust it forward by such engagement also through adaptable also for engagement with the outer end of the work when the work is of 20 lesser length. Another object is the provision of means for locking the pusher plate at various heights in relation to its handle 25 or supporting means. Other objects will appear from time to time in the course of the specification and claim.

I illustrate my invention more or less diagrammatically in the accompanying drawings, wherein—

Figure 1 is a front elevation;

Figure 2 is a section on the line 2—2 of Figure 1;

Figure 3 is a similar section with parts 35 in different position;

Figure 4 is a plan view;

Figure 5 is a section on the line 5—5 of Figure 3;

Figure 6 is a section on the line 6—6 of 40 Figure 1; and

Figure 7 is a section on the line 7—7 of Figure 6.

Like parts are indicated by like symbols throughout the specification and drawings.

Referring to the drawings, A generally indicates the base of a slicing machine and A¹ supports upon which the base is mounted.

B indicates a rotary knife forwardly recessed as at B¹. B² is a pulley for said knife, knife and pulley being mounted for example

on the knife shaft B³. B⁴ indicates a belt passing about the pulley B² whereby the pulley and knife may be rotated, for example in response to the rotation of the motor not herein shown.

C indicates a guard plate for the front of the knife it being provided with an arcuate edge C¹ which penetrates the recess B¹ of the knife. As seen in Figure 4 the axis of the knife is tilted somewhat from perpendicularity to the face of the plate C, in order to bring the cutting edge of the knife forwardly of said guard plate.

D generally indicates the gauge plate mounted in any suitable support D¹ which may be moved by any suitable means toward and away from the cutting plane of the knife.

E indicates a track or rail, herein shown as of circular cross-section, and E¹ is a guide rail positioned therebeneath and herein shown as of rectangular cross-section. E² generally indicates a work supporting carriage which is slidably mounted on the rail E and is supported thereby. Depending from the carriage are the lugs E³, which are positioned on opposite sides of the track E¹.

E⁴ are supporting members, for example screws, whereby a certain pivotal adjustment of the carriage about the rail E may be obtained. E⁵ indicates a work supporting plate which, together with the abutment flange E⁶ is mounted on any suitable supporting member or frame E⁷ pivoted as at E⁸ to the carriage E². E⁹ E¹⁰ are guard members associated with the support E⁵ and its flange E⁶.

G generally indicates a pusher plate which is provided on its forward face with the work engaging studs or spikes G¹. Its lower edge is irregularly formed as at G² and may be further provided with the work engaging spikes or prongs G³, in Figures 2 and 3 indicated as forwardly inclined toward the cutting plane. G⁴ indicates a guide pin for the pusher plate, the pin being mounted on the bracket G⁵ associated with the supporting structure E⁷. Slidably mounted on the pin G⁴ is the sleeve G⁶ from which projects the member G⁷ associated with the manual handle G⁸.

The outer end of the handle G⁸ is secured in relation to the sleeve G⁶ the forward end of

which is headed as at G¹⁰. The head portion G¹⁰ is formed with a forward slot G¹¹ with the inclined side walls G¹². G¹³ indicates a block, associated with the plate G, having inclined faces G¹⁴ opposed to the inclined walls G¹². G¹⁵ is any suitable pin or connection whereby, in response to rotation of the locking knob G¹⁶ the block G¹³ may be locked in position at any desired point along the channel G¹¹. G¹⁷ indicates a further lateral extension from the sleeve G⁹ which terminates adjacent the edge of the support E⁵ opposite to the pin G⁴. It may be provided with an anti-frictional member G¹⁸ opposed to a bearing portion G¹⁹ along the edge of the support E⁵.

15 It is desirable to limit the uppermost adjustment of the pusher plate G and likewise to prevent accidental dropping of the pusher plate upon the upper surface of the support E⁵. Any suitable means may be employed.

20 For example, as illustrated in Figures 2, 3, 5 and 6, the squared head G²⁰ of the pin G¹⁵ is seated within the recess G²¹ in the block G¹³. The pin G¹⁵ projects through an elongated aperture G²², which defines the lowest position of the pusher plate as shown in Figure 2. The pusher plate G may be raised until the head G²⁰ engages the wall G²³ of the recess G²¹ shown in Figure 3.

25 It will be realized that whereas I have described and shown a practical and operative device, nevertheless many changes might be made in the size, shape, number and disposition of parts without departing from the spirit of my invention. I therefore wish my description and showing to be taken as in a broad sense illustrative and diagrammatic rather than as limiting me to my specific showing.

30 The use and operation of my invention are as follows:

In the employment of a slicing machine of the type herein shown it may be desirable to slice material having lengths greater than the length of the support E⁵. For example, in slicing a piece of bacon the bacon may extend outwardly away from the knife for a distance considerably exceeding the length of the pin G⁴ or the width of the plate E⁵. In such case it is desirable to grasp the top of the bacon, it being impossible to place the pusher plate against its outer end. However, when so engaging the bacon, if the plate G is left in the position of adjustment in which it is shown in Figures 1 and 2 and merely tilted about the pivot G⁴, it will not evenly engage the top of the bacon. I therefore provide a range of adjustment for the plate in relation to the handle G⁸. This handle, in connection with the members G⁷ and G¹⁷, forms a supporting structure which extends from edge to edge of the plate E⁵, namely, from the pin G⁴ to the bearing G¹⁹. I find it desirable to leave this structure normally in the position in which it is shown

in Figure 1, and to provide means for raising or lowering the pusher plate G in relation to it. The wedge faced block G¹³ and channel G¹¹ form an efficient locking means. The locking nut G¹⁶ can be quickly loosened, and as quickly tightened. When the plate G is locked in the upper position, in which it is shown in Figure 3, its serrated lower edge engages the top of the work, and the pins G³ further help in grasping the work. In order to ease the movement of the work towards the cutting plane I may corrugate the entire upper surface of the plate E⁵, as shown at E¹¹ in Figures 1 and 4. These corrugations or ridges support the work but vastly reduce the area of frictional engagement with the plate E⁵. The area G¹⁹ may be milled or smoothed to form an adequate bearing support for the member G¹⁸. If the member G¹⁸ wears down or is omitted, the outer end of the member G¹⁷ engages the bearing G¹⁹ and since the opposed areas are relatively slight and since the bearing G¹⁹ is milled or smoothed, an adequate support is provided which does not perceptibly interfere with the forward movement of the pusher plate assembly toward the cutting plane.

I claim:

In a slicing machine, a rotary knife, a carriage and means for guiding said carriage along a path across the face of the knife, a pusher plate support mounted for movement on said carriage toward and away from the face of the knife and a pusher plate vertically adjustably mounted thereupon, the connection between pusher plate and pusher plate support including a wedge block on one of said members opposed to a wedge cavity in the other, and locking means for drawing said block into said cavity.

Signed at Indianapolis, county of Marion and State of Indiana, this 24th day of June, 1929.

WILLIAM J. CAMPBELL.
